UNITED STATES PATENT OFFICE

SAMUEL HAMMER, OF BROOKLYN, NEW YORK, ASSIGNOR TO UNITED METAL BOX CO.
INC., OF BROOKLYN, NEW YORK, A CORPORATION OF NEW YORK

CONSTRUCTION OF DOORS

Application filed October 11, 1928. Serial No. 311,728.

This invention relates to improvements in the construction of doors, especially doors carrying mirrors and designed for cabinets, small closets for medicines and toilet articles, 5 and other uses.

An object of the invention is to provide a door upon which a mirror can be secured to the outer face, without the drilling of holes in the mirror for fastening devices; and still 10 be firmly held in place with a fully finished and attractive appearance.

A further object of the invention is to provide a door made of parts that can readily be assembled and detached, and including 15 fastening devices that can easily be applied, or loosened and removed, thus rendering the door easy to mount or to take down in case any of its parts need to be repaired.

Preferably the door and the securing 20 means are of metal, stamped or otherwise worked into the required size and shape.

The nature and advantages of the invention are further set forth in the following description which, taken with the drawings, 25 discloses a preferred form of my invention. I may, however, resort to changes not illustrated herein but nevertheless come within the principle of the invention and embraced within the scope and meaning of the broad 30 terms in which the appended claims are expressed.

Figure 1 is a front view of a door construction according to my invention;

Figure 2 is a rear view thereof;

Figure 3 is a section on the line 3—3 of 35 Figure 1 looking downward;

Figure 4 is a rear elevation of the front part of the body of the door;

Figure 5 is a section on the line 5—5 of 40 Figure 4 looking upward; and

Figures 6 and 7 are perspective views showing details.

On the drawings the same numerals identify the same parts throughout.

The door is adapted to support a mirror 45 shown at 1 large enough to cover the whole of the outer face of the door and etched or ground or otherwise worked to carry an ornamental design if desired. The body of the 50 door comprises two principal parts, one of

which is a metal plate indicated at 2; this plate forming the outer portion of the door and intended to bear the mirror 1 which is securely attached thereto but spaced from it by an intervening sheet of suitable material 55 such as cardboard 3. The other principal part of the door is the back plate 4 which is fastened to the front plate 2 and this rear plate carries the hinges by which this door is pivotally mounted in position to control 60 the entrance to the enclosure with which it is used. As stated, the parts 2 and 4 are preferably of metal and they can be made by stamping so as to give them the proper shape and turn up the edges thereof to provide rims 65 which enable the front plate 2 and back plate 3 to be assembled in such a way that the rim of the back plate telescopes within the rim of the front plate. As will be shown later, to attach the mirror to the door, it is desirable 70 to avoid drilling holes in the glass and for this reason I provide the front plate 2 with tongues 5 which are cut and bent to the rear at a suitable number of points along the sides, top and bottom. Adjacent these 75 tongues and formed by the bending back of the tongues, openings are provided in the front plate 2, as indicated at 6 in Figure 5. These openings receive engaging devices 7 having bent-over ends 8 and 9; the ends 8 80 are turned until they are at right angles with the body of the engaging devices 7, while the opposite end 9 of each engaging device is somewhat shorter and is not quite perpendicular to the central part of the device 85 or parallel with the other end. This is for the purpose of making the ends 9 fit flatly against the beveled edges or periphery 10 of the mirror 1; the ends 9 of the engaging devices project through the apertures 6 of the 90 front plate 2 while the opposite ends 8 are to the rear of this plate with the edges of their extremities adjacent the tongues 5. Co-operating with the engaging devices I am 95 employ fastening means 11 which are in the form of resilient strips of metal having diagonally bent ends 12 which are turned up at 13. These members are slipped beneath the ends 8 of the engaging devices 7, and between these devices and the tongue 5. The 100

- central parts 11 of these fastening members pass under the larger ends 8 of the engaging devices and are disposed so as to hold these engaging devices in securing position.
- 5 Therefore to attach the glass to the door the engaging devices are merely put successively through the apertures 6 in such a way that the ends 9 are caused to engage the beveled edge 10 of the mirror 1, with the opposite ends 8 adjacent the ends of the tongues 5, and then the fastening members are forced under the ends 8, and between these engaging devices and the tongues; whereupon each of the devices 7 is located in place and the mirror 1 is securely held. By reason of the fact that the members 11 are made of resilient metal they can easily be forced into position and the ends 12 thereof are long enough to make the central part of each of these members push the engaging devices back, by pressing on the ends 8 to a sufficient extent to hold the mirror 1 tightly on the front plate 2 and compress it against the sheet of cardboard 3.
- 10 20 25 30 35 40 45 50 55 60
- As stated above, the front plate 2 is made so that it has a rearward extending rim 14 around the periphery thereof and on the rear surface are secured by spot-welding, or otherwise, a pair of angle-plates 15 having strengthening flanges 16 turned up from the rear surface of the plate 2. These plates 15 are apertured to give passage to securing elements 17 which may have the form of screws with their heads between the plates 15 and the plates 2.
- The back plate 4 is made with a peripheral rim 18 which fits within the rim 14; this plate thus covers the tongue 5, fastening members 11, and the inner ends 8 of the engaging devices 7. On its outer face the rear plate 4 may carry hinged members 19 on one edge to enable it to be hung up on similar hinge members at the entrance to the enclosure, and it may also carry projecting in a rearward direction a catch 20 to engage a suitable part at the edge of the enclosure and hold the door shut. It may also bear one or more projections 21 to serve any necessary purpose. In line with the securing element 17 the rear plate 4 may be perforated, as indicated at 22 and through the perforations 22 I may pass sleeve nuts, for example, to secure the front and back plates 2 and 4 together. The angle-plates 15 may be punched as indicated at 23 on Figure 5, to provide recesses for the heads of the screws 17 between the plates 15 and the front plate 2, so that the plates 15 can engage flatly with the rear surface of the front plate 2.

When the parts of the door are assembled the rear plate 4 with its rim or peripheral flange 18 fits within the rim or flange 14 of the front plate and the two plates are held by the elements 17 and the sleeve nuts or

screws for same. Whenever necessary the two plates can be taken apart merely by removing the securing elements cooperating with the screws 17; and likewise the mirror 1 can be dismounted at any time merely by pulling out the fastening members 11 and withdrawing from the aperture 6 the engaging devices 7.

The mirror 1 is almost equal in size to the front plate 2 and the method of mounting this mirror by attaching to the door without drilling the holes through the mirror is a feature of decided superiority, because it not only saves labor upon the glass but it also avoids the risk of breaking the glass by drilling therethrough; and the border of the front plate 2 surrounding the beveled edges 10 of the mirror tends to render inconspicuous any defects or flaws in the edge of the mirror and adds to the finished appearance of the entire article.

I have above referred to the novel features of my present invention as employed for the purpose of attaching a mirror panel to the face of a cabinet door. However, it will be apparent that this invention might also be applied to various other analogous purposes or uses where a simple and reliable means for easily, quickly and securely attaching an ornamental panel to a support structure is desired.

I claim:—

1. A door construction comprising a mounting plate, a mirror having beveled edges disposed upon one face of the plate, the edges of the plate overlapping the edges of the mirror, the plate being cut to provide rearward-extending tongues and having openings adjacent said tongues, engaging devices in said openings projecting beyond both faces of the plate, said devices having one end bent to engage the beveled edge of the mirror and having its opposite end bent to form an abutment, and resilient members having bent ends disposed between the engaging devices and said tongues and between the plate and said abutments of the engaging devices to hold the latter in securing position.

2. A door construction comprising a plate, a mirror secured to one face of the plate, said plate having a circumferential rim turned away from the mirror, angle-shaped plates secured to the first-named plate on the face turned away from the mirror, and securing elements passing through the angle-shaped plates and held fast thereby.

3. A door construction comprising a plate having a mirror on one face, a circumferential rim projecting from the opposite face, angle-shaped plates secured to said opposite face, securing elements held fast by said angle-shaped plates and projecting through the latter, and a plate having a rim telescoping within the rim of the first-named plate.

to be held fast thereto by said securing elements.

4. In combination, a supporting structure having a front surface disposed in a single plane, a panel of slightly less dimensions than said support superimposed on said surface and substantially conforming in outline contour to the supporting structure, attaching members for said panel transversely movable through apertures in the supporting structure adjacent its marginal edges, and means coacting with each of said members and with the supporting structure to retain said members in their attaching positions with their outwardly projecting ends in bearing contact upon the marginal edges of said panel.

5. In combination, a supporting structure having a front surface disposed in a single plane, a panel of slightly less dimensions than said support superimposed on said surface and substantially conforming in outline contour to the supporting structure, attaching members for said panel transversely movable through apertures in the supporting structure adjacent its marginal edges, the opposite ends of said members being angularly bent and extending inwardly from the marginal edges of said panel, and resiliently acting elements interposed between the inner ends of said members and the supporting structure to retain said members in attaching position and yieldably urge said panel into bearing contact with the surface of the supporting structure.

6. In combination, a supporting structure having a front surface disposed in a single plane, a panel of slightly less dimensions than said support superimposed on said surface and substantially conforming in outline contour to the supporting structure, attaching members for said panel transversely movable through apertures in the supporting structure adjacent its marginal edges, and leaf spring members having central portions interposed between the inner ends of said members and the supporting structure and in bearing contact at their opposite ends with the rear face of said structure in spaced relation from the attaching members, whereby the latter are yieldably held in their attaching positions and caused to constantly urge said panel into bearing contact with the outer surface of the supporting structure.

55 7. A door having openings therethrough, a mirror, clip members extending through the openings in the door from the back and having fingers engaging the mirror, and resilient cushion means reacting against the door-back and serving to exert thrust on the clip members behind the door to thereby clamp the mirror by the clip fingers snugly but yieldably against the door.

8. A door having openings therethrough, 65 a mirror, clip members having fingers ex-

tending through the openings and engaging the mirror, cushion means reacting against the door-back and against parts of the clip members, respectively, to snugly but yieldably clamp the mirror on the door by the 70 clip member fingers, and a flanged cover plate detachably mounted on the door-back and arranged to enclose the parts of the clip members projecting backwardly from the door.

In testimony that I claim the foregoing as 75 my invention, I have signed my name hereto.

SAMUEL HAMMER.
